(74) Attorney, Agent, or Firm — MLO, a professional corp.

(57) **CLAIM**

The ornamental design for a smart lock, as shown and described.

DESCRIPTION

FIG. 1 is a perspective view of a smart lock showing our new design;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view of the design in a state of use. The dot-dash broken lines are for purposes of illustrating environmental structure only and form no part of the claimed design.
